ARTICLE OF MANUFACTURE

Clyde N. Stover, Baltimore, Md. assignor to
 Western Electric Company, Incorporated, New
 York, N. Y., a corporation of New York

Application October 4, 1938, Serial No. 233,179

9 Claims. (Cl. 174—112)

This invention relates to an article of manufacture, and more particularly to an insulated electrical conductor.

In various phases of the electrical art it is desirable in many instances to be able to distinguish one electrical conductor from another in dark or poorly lighted places where distinguishing characteristics are not visible.

Objects of the invention are to provide a simple, efficient and practical article of manufacture.

With these and other objects in view, one embodiment of the invention comprises an electrical conductor having a covering formed thereon with indicating variations rendering the conductor not only visually distinguishable from others but distinguishable therefrom by the sense of touch.

Other objects and advantages will be found in the following detailed description when taken in conjunction with the accompanying drawings, wherein

Fig. 1 is a vertical sectional view of a knitting machine by the aid of which the article may be manufactured;

Fig. 2 is a vertical sectional view of the cams for actuating the needles;

Fig. 3 is a schematic illustration of the relationship between the needles, cam lobes and thread supplies for forming one type of article;

Fig. 4 is a similar schematic illustration of the relationship between the needles, cam lobes and thread supplies for forming another type of article;

Figs. 5 and 6 are plain developments showing the patterns of the knitted structures made with the apparatus conditioned in accordance with Figs. 3 and 4 respectively, and

Figs. 7 and 8 are fragmentary views of articles, respectively including the knitted coverings shown in Figs. 5 and 6.

Referring now to the drawings, particularly Fig. 1, the apparatus, by the aid of which the article may be manufactured, is shown mounted in a housing 11 having two upwardly extending standards 12, which carry a cross piece 13 supporting a tubular member 14, through which a core 9, such as an electrical conductor to be covered with a knitted tubular covering, is passed. Attached to the downwardly projecting portion of the tube 14 is a disk 15 which supports a plurality of adjustable thread guides 16, each of which is provided with an eyelet in its lower end through which a thread 18 from one of the several thread supplies is guided to the knitting head. The threads passing through the thread

guides are withdrawn from stationary cops (not shown) from which the threads are removed over one end of the cops without rotating the cops, as is well known in the art.

5   Mounted in the housing 11 is a needle bed or cylinder 17 having radial slots 18 cut therein in which needles 19 are adapted to reciprocate. The upper ends of the needles are held onto the needle cylinder by a disk 21 made in two sections and secured in place by a nut 22. The needle cylinder 17 is mounted on a cylindrical support 23 having a pair of diametrically opposite slots 24 which coincide with similar slots on the lower portion of the needle cylinder, and keys 25 are placed 10 in these slots to permit the needle cylinder to move longitudinally with respect to the support 23, but relative rotational movement is prevented by the keys. The lower end of the needle cylinder is threaded and a sleeve 26 is inserted into the lower end of the cylinder support 23 and is threaded onto the needle cylinder. A lock nut 27 is threaded into the lower end of the cylinder support and engages the sleeve 26 to retain the sleeve in position.

15   Surrounding the needle cylinder is a cam housing 28 supported upon a cylindrical cam support 29. The needle cylinder and the needle support are journaled in ball bearings 31 and 32 in the cam support 29, and the entire rotating mechanism is supported in a ball bearing 33 mounted in the lower portion of the housing 11 and a bearing 34 in the upper portion of the housing.

20   Within the cam housing 28 is a lower cam section 35 which fits into the cam housing, and rotation relative to the cam housing is prevented by a key 36. The upper cam section 37 is spaced from the lower cam section, to form a groove into which the butts 20 of the needles project, by a ring 38 which fits snugly within the cam housing. The upper cam section is similarly held 25 against rotation relative to the cam housing by a key 39. In order to hold the several sections of the cam in place an annular ring 41 is threaded onto the cam housing 28.

25   In operating a knitting machine it is frequently necessary to remove certain of the needles or change one or more of the needles which become broken or defective, and it is desirable to be able to do this without removing the entire needle cylinder from the apparatus. For this purpose a slot is formed in the upper cam section, and a key 42 which normally closes the slot is placed 30 therein. This key has a sloping portion 43 which corresponds to the slope of the cam groove at 35 this point. Thus when it is desired to remove a

needle the nut 22 and disk 21 are removed from the upper end of the cylinder; then the annular ring 41 is removed, which permits the key 42 to be withdrawn from the slot. The cylinder may then be rotated relative to the cam so that any one of the needles is in alignment with the slot and may be withdrawn upwardly from the needle cylinder without removing the needle cylinder from the machine.

It is preferable to place the slot through which the needles are drawn on the leading slot of a cam lobe in the direction of rotation of the cam. Referring to Fig. 2, if it is assumed that the portion of the cam having the slot therein moves from left to right, it will be noted that the butt of the needle will ride on the lower side of the cam slot while the needle removing slot is on the upper side of the cam slot. By thus arranging these parts it has been found that the key 42 may be omitted from the slot without interfering with the operation of the needles.

The cam support 29 may have a beveled gear 44 integral therewith, and the cylinder support 28 may have a beveled gear 45 secured thereto. Cooperating gears 46 and 47 are mounted on a drive shaft 48 and, in the particular embodiment of the invention illustrated, the cam is rotated at three times the speed of the needle cylinder and in the same direction.

During the operation of the knitting machine the needle cylinder 17 and the cams 35 and 37 are rotated at different speeds relative to the stationary thread supplies and if the needles 18 were equally spaced in the cylinder a knitted pattern as illustrated in my copending application Serial No. 218,301, filed July 9, 1938, would be formed with equally spaced wales forming a covering, on the conductor threaded through the machine, substantially uniform or even throughout its circumference.

By placing another needle, as indicated at 50 (Fig. 3), between two of the equally spaced groups of needles in the cylinder an additional wale may be added to the covering 51 without varying the positions of the original wales. This additional wale results in the forming of an identifying rib 52 (Figs. 5 and 7), as the threads forming the loops in this added wale tend to lie between the loops of the adjacent wale, but as there is not sufficient space upon the circumference of the core for the three closely adjacent wales the additional wale is forced outwardly or caused to lie somewhat upon its adjacent wales. As illustrated in Fig. 5, the wales extend spirally about the core and the courses extend longitudinally thereof. The rib 52 formed by the added wale therefore is formed spirally about the core and may be visually distinguished from other uniformly covered cores. Furthermore, in dark or poorly lighted places a person may readily distinguish a core covered as illustrated in Figs. 5 and 7 by passing his fingers longitudinally of the covered core and in so doing will bring them in contact with the rib. If desired, other needles may be disposed between others of the equally spaced needles to form, if desired, more than one identifying rib.

The arrangement shown in Fig. 4 is to condition the knitting machine to form a covering on the core with a different type of tracer or identifying means. The type of tracer formed by this illustration of the machine is a depression or groove in the covering formed on the core. This is accomplished by removing one or more of the original equally spaced needles in the carrier. As

a result thereof one or more of the wales is removed without disturbing the positions of the other wales. In Fig. 6 one of the wales is shown removed to provide an identifying portion 53, and in this space lie only longitudinal thread bars connecting the spaced wales 54 and 55. The entire covering 56 is therefore formed of a group of equally spaced spirally extending wales, formed of the interconnecting loops of the successive strands, spaced readily determined distances by merely the thread bars of the various strands to form a spiral identifying groove or depression. This depression or groove is not only visually noticeable in a suitably lighted place but is readily noticeable by the sense of touch in a dark or poorly lighted place.

In various fields of the electrical art the conductors are disposed in pairs or groups and it is frequently desirable to distinguish certain of the conductors from the others. Although it is possible to cover the conductors with coverings formed of different color threads, making it possible to visually distinguish one from the other in a suitably lighted place, the variations in color do not aid in their distinction unless sufficient light is provided. Therefore, even in darkness conductors having coverings formed with the uneven identifying portions such as the ribs or depressions or both may be readily selected. The term "uneven identifying portions" is applicable to either embodiment as the majority of the needles are equally spaced and the portion of the covering formed by these needles will be even and uniform throughout, while the variations from the even portion, caused by the addition of a needle between two of the equally spaced needles or the removal of one of the equally spaced needles, will be noticeable, not only visually but by the sense of touch where light is not sufficient for visual identification. In both embodiments the thread used in knitting the coverings is of sufficient size so that the uneven identifying portions are readily noticeable.

The embodiment of the invention herein disclosed is illustrative only and may be widely modified and departed from in many ways without departing from the spirit and scope of the invention as pointed out in and limited only by the appended claims.

What is claimed is:

1. An article of manufacture comprising an electrical conductor core, and a knitted covering for the core formed of interconnected wales, certain of which are unevenly spaced to form an identifying portion in the covering.

2. An article of manufacture comprising an electrical conductor core, and a knitted covering for the core formed of interconnected wales, certain of which are unevenly spaced to form an outwardly projecting identifying rib portion in the covering.

3. An article of manufacture comprising an electrical conductor core, and a knitted covering for the core formed of interconnected wales, certain of which are unevenly spaced to form an outwardly projecting identifying rib portion spirally about the core in the covering.

4. An article of manufacture comprising an electrical conductor core, and a knitted covering for the core formed of interconnected wales, certain of which are unevenly spaced to form an inwardly extending identifying depression in the covering.

5. An article of manufacture comprising an electrical conductor core, and a knitted covering

for the core formed of interconnected wales, certain of which are unevenly spaced to form an inwardly extending identifying depression spirally about the core in the covering.

6. An article of manufacture comprising an electrical conductor core, and a knitted covering for the core formed of a plurality of equally spaced wales and an additional wale disposed adjacent two of the equally spaced wales and projecting outwardly therefrom to form an identifying rib in the covering.

7. An article of manufacture comprising an electrical conductor core, and a knitted covering for the core formed of a plurality of equally spaced wales and an additional wale disposed adjacent two of the equally spaced wales and

projecting outwardly therefrom to form an identifying rib in the covering spirally about the core.

8. An article of manufacture comprising an electrical conductor core, and a knitted covering for the core formed of a plurality of equally spaced wales and two of the wales spaced a greater distance apart to form an identifying depression in the covering.

9. An article of manufacture comprising an electrical conductor core, and a knitted covering for the core formed of a plurality of equally spaced wales and two of the wales spaced a greater distance apart to form an identifying depression in the covering spirally about the core.
